UNITED STATES PATENT OFFICE.

FRANZ YOKEL, OF MERIDEN, CONNECTICUT, ASSIGNOR TO THE MERIDEN BRONZE COMPANY, OF SAME PLACE.

DESIGN FOR A LAMP.

SPECIFICATION forming part of Design No. 21,871, dated September 27, 1892.

Application filed August 1, 1892. Serial No. 441,877. Term of patent 3½ years.

To all whom it may concern:

Be it known that I, FRANZ YOKEL, of Meriden, in the county of New Haven and State of Connecticut, have invented a new Design for 5 Piano-Lamps; and I do hereby declare the following, when taken in connection with accompanying drawing, to be a full, clear, and exact description of the same, and which said drawing constitutes part of this specification and 10 represents a perspective view.

This invention relates to a design for that class of lamps which are supported on a standard from the floor and commonly called "piano-lamps;" and the design consists in the 15 configuration of the support, as shown in the accompanying illustration.

The support represents three square legs, but of serpentine shape, represented as connected near their upper ends, and also at a 20 point below, by an ornamented disk, each of the legs represented as twisted for a portion of its length from the upper end downward,

the legs represented as projecting above the disk which connects them and curved outward and represented as carrying a spherical 25 ornament at their tips, the main standard represented as rising from the lower connection and extending through the upper connection, the legs above the connection forming ornamental branches, and the standard 30 represented as carrying the fount upon its upper end, as shown in the accompanying illustration.

I claim—

The design for a piano-lamp, as herein described and shown.

In testimony whereof I have signed this specification in the presence of two subscribing witnesses.

FRANZ YOKEL.
